STEREOTYPE CASTING MOLD

Robert T. Edwards, New York, N. Y., assignor to
 R. Hoe & Co., Inc., New York, N. Y., a corporation
 of New York; Irving Trust Company,
 permanent trustee

Application November 18, 1931, Serial No. 575,769

10 Claims. (Cl. 22—5)

The invention relates to molds for casting stereotype printing plates from matrices and as herein disclosed, provides a casting mold having two casting chambers that may be brought into operation alternately. Thus, after a plate is cast and while the metal is hardening, the operator may prepare the second mold for the next casting operation. This preparatory work being completed, the second mold is then closed and the first mold is simultaneously opened. It has been found that by the use of such a mold, a single operator can produce fully twice as many plates as when using a mold of the usual form.

An object of the invention is to provide a casting mold that will reduce the time required for casting a number of plates.

Another object of the invention is to provide a casting mold having two casting chambers that may be used in alternation, and so arranged that the operator may prepare one chamber for casting a plate, while a plate previously cast in the other chamber is cooling.

Another object of the invention is to provide a casting mold having matrix holding gauges that may be quickly adjusted for casting plates of different widths.

It is also an object of the invention to provide a plate casting mold of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings, wherein:

Figure 1 shows a side view of the improved casting mold in position where one casting chamber is closed and the other is opened;

Figure 2 shows a vertical elevation of the mold as seen in the direction of arrow 2 of Figure 1;

Figure 3 shows a sectional plan view of a portion of the mold as viewed on the line of arrow 3 of Figure 1;

Figure 4 shows a fragmentary view of a por-

tion of the mold illustrating portions of one of the adjustable side gauges; and

Figure 5 is a fragmentary view partly in section showing details of the side gauge supporting mechanism as seen in the direction of arrow 5 of Figure 4.

Referring to the drawings, 11 indicates a base frame to which a double faced fixed casting mold member 12 is secured. A support 13, is pivotally carried on screws 14 secured to the fixed mold member 12 and movable mold members 15 and 16 are secured to the supports 13 by means of screws 17. It will be seen that the mold members 15 and 16 are fixed with relation to each other by the common support 13 and they may be swung about the pivots 14 so as to bring either mold into casting relation with the fixed mold member 12, and that when either mold member is in such relation, the other one is in the horizontal or open position.

Latches 18 are pivotally supported on screws 19, secured to the fixed mold member 12, and centering springs 21, act to bias the latches 18 to the position shown in Figure 1. Locking shafts 22 are rotatably supported in each of the movable mold members 15 and 16 and are provided with heads 23, in the faces of which, locking pins 24 are eccentrically supported. Operating levers 25 are secured to the locking shafts 22, and it will be seen that when a shaft is rotated the pins 24 will cooperate with the latches 18 to draw the movable member into close relation with the fixed mold member. The handle of the mold member 15, as shown in Figure 1, is moved to the unlocked position. The handle of the mold member 16, as shown in full lines in Figure 1 is in a partially unlocked position and as in dotted lines is in the fully locked position.

A spring 26 is arranged to bear against a hub of the lever 25 and acts to hold it in either the locked or unlocked position. Disengaging pegs 27 in the locking pins 24 are so placed that when the handle is moved upward, they operate to raise the latch 18 and thus release the mold.

Spring bumpers are furnished to cushion the fall of the movable mold members when they are turned to the open position, and comprise coil springs 28, one end of each of which is secured to a rod 29 that is supported in brackets 31 secured to the mold member 12. The opposite ends of the coil springs are extended and connected to rods 32 which engage with striking plates 33 secured to the movable mold members. Handles 34 are provided at each side of the movable mold members for convenience in operation. The

spring bumpers also serve to maintain the movable mold members approximately in balance, the weight of the adjacent movable mold member when in the horizontal position being practically 5 counterbalanced by the spring 28, then exerting its greatest pressure, thus permitting the manipulation of either mold member with a minimum effort on the part of the operator, in a position where ordinarily the maximum effort of the operator is required. As the horizontally positioned 10 movable mold member swings upwardly and the vertically positioned mold member swings downwardly, the lessening effect of the spring is compensated for by the weight of the descending 15 mold member so that equilibrium is approximately maintained regardless of the position of the movable mold members.

In the embodiment of the invention shown, provision is made for cooling the fixed mold member 20 by means of circulating a suitable fluid through cavities in the member in accordance with well known practice, and the movable mold members are preferably formed with ribs to dissipate the heat incident to the casting operation.

The fixed mold member 12 is provided with casting surfaces on its opposite sides, each of 25 which form one side of a mold chamber, the opposite side being formed by the adjacent surface of the movable mold member when it is moved into casting position. The bottoms of the 30 casting chambers are formed by head gauges indicated at 35, and the narrow sides of the casting chamber which form the side edges of the plate, are formed by a novel arrangement of side gauges 35 which are adjustable to receive matrices of various widths. The body of each of these gauges is indicated by the numeral 36, and is provided with extended arms 37, which are slidably supported in hinge members 38, that are pivotally supported 40 in brackets 39, secured to the frame of the movable mold members 15 and 16.

A spring 41 acts on a plate 42 to turn the hinge member on its pivot 43 and press the side gauge 45 against the surface of the casting mold member. An operating bar 44 is secured to the extended arms 37 and provides a convenient handle whereby when the mold is opened, the side gauges may 50 be moved toward or away from each other to accommodate matrices of various widths, and the spring members being provided with but little clearance for the passage of the arms 37, the side gauges 36 will be maintained in parallelism with each other.

In operation, with the mold member 15 in the 55 position shown in Figure 1, a matrix from which it is desired to cast a plate is placed in position with one edge adjacent the head gauge 35. The operator then moves the side gauges into position so that they slightly overlap the edge of the matrix, and when he releases the handles the gauges are pressed down on the matrix by the 60 springs, thus securing the matrix in position. It is also customary to insert a piece of cardboard of the same width as the matrix, in position slightly overlapping its upper edge and extending up to the top of the mold, in order to prevent molten metal from running down behind the matrix. The mold is then moved to the vertical position 65 corresponding to the position in which the member 16 is shown in Figure 1, and locked by operation of the lever 25. The plate is then cast in accordance with the usual practice.

It will be noted that the mold member 16 is 70 moved away from the position shown in Figure 1 simultaneously with the moving of the member 15

to the casting position, and the operator may then place another matrix in position on the mold member 16, while the plate cast against the mold member 15 is cooling. The mold member 16 will then be moved into casting position and the plate removed from the mold member 15. It will thus be seen that the plates may be cast successively without the operator losing time in waiting for the plates to cool between casting operations, for the time necessary for cooling is 10 occupied in the preparation of the mold for casting the succeeding plate. The side gauges 36 are formed with enlarged tail pieces 45 which overlap the funnel-shaped channels 46 that are formed in the movable mold members, the purpose of 15 these being to prevent the molten metal from running outside the gauges when they are moved close together in casting narrow plates.

What I claim is:

1. In a stereotype plate casting device, a fixed 20 mold member, and two movable mold members arranged to swing about a common axis and alternately cooperate with opposite faces of the fixed member to form casting molds.

2. In a stereotype plate casting device, a fixed 25 mold member, two movable mold members arranged to swing about a common axis and alternately cooperate with opposite faces of the fixed member to form two casting molds, and means for simultaneously moving the movable members. 30

3. In a stereotype plate casting device, a double 35 faced mold member, a pivoted support rotatable with respect to the double faced member, and two single faced mold members secured to the support.

4. In a plate casting device, a fixed member having two mold faces, two movable members pivotally supported to move about a common axis with respect to the fixed member and each having a mold face adapted to cooperate with a 40 mold face on the fixed member to form a casting mold, and means for locking either of the movable members to the fixed member when the other member is disengaged therefrom.

5. In a stereotype plate casting device, a fixed 45 mold member, a movable mold member adapted to receive a matrix, side gauges on the movable mold member, springs for the side gauges arranged to hold the matrix in position when preparing to cast a plate, and means for adjusting the side gauges laterally to cast plates of various widths. 50

6. In a stereotype plate casting device, a fixed 55 mold member, a movable mold member adapted to receive a matrix, a pair of side gauges adapted to yieldingly hold the side edges of the matrix in position preparatory to casting a plate, and means for adjusting either side gauge with respect to the other while maintaining the said gauges in parallelism. 60

7. In a stereotype plate casting device, a fixed 65 mold member, a movable mold member adapted to receive a matrix, a plurality of side gauges, and hinge members pivotally supported on the movable mold member and adapted to adjustably support the said gauges whereby they may be adjusted to hold matrices of various widths. 70

8. In a device for the casting of stereotype plates, a first mold member, a second mold member adapted to receive a matrix, spring biased members hingedly supported on the second mold member, and side gauges connected to the hinged members and adjustable with respect thereto to hold matrices of various widths. 75

9. In a device for the casting of flat stereotype 75

plates, a fixed member having two mold faces, two single faced mold members movable simultaneously about a common axis and alternately into cooperative relation with the double faced member to form casting molds, and weight counteracting means acting on each movable mold member to maintain the single faced mold members approximately in balance.

5 10. In a device for the casting of stereotype

plates, a fixed member having two mold faces, two single faced mold members movable simultaneously about a common axis and alternately into cooperative relation with the double faced mold members for casting molds, and spring pressed means engageable with each movable mold member to maintain same approximately in balance.

5

ROBERT T. EDWARDS.
